UNITED STATES PATENT OFFICE.

EGGLESTON SMITH, OF MAMARONECK, NEW YORK, ASSIGNOR TO EGGLESTON DRILLING CORPORATION, OF DOVER, DELAWARE, A CORPORATION OF DELAWARE.

FEEDING-PRESSURE REGULATOR FOR EARTH-BORING BITS.

Application filed January 21, 1925. Serial No. 3,711.

To all whom it may concern:

Be it known that I, EGGLESTON SMITH, a citizen of the United States, residing at Mamaroneck, in the county of Westchester, 5 State of New York, have invented certain new and useful Improvements in Feeding-Pressure Regulators for Earth-Boring Bits; and I do hereby declare the following to be a full, clear, and exact description of the invention, such as will enable others skilled in 10 the art to which it appertains to make and use the same.

This invention relates to earth-boring such, for example, as in drilling in connection with mining operations or in drilling for oil, water, gas, and the like. More particularly, the object of the invention is the provision of improvements in applying, regulating, or controlling the feeding pressure of earth-boring bits.

In carrying on drilling operations of this character, it is important, in order to obtain the maximum rate of cutting, to apply the correct drilling or feeding pressure to 25 the bit. The correct feeding pressure to secure maximum cutting speed varies with the different materials or formations encountered by the earth-boring bit. The subject of proper feeding pressure is of especial importance when earth-boring bits constructed 30 of abrasive material, such as carborundum or the like, are employed.

Among other things the present invention affords a means for applying a feeding pressure, which means is semi-automatic in operation, which is relatively easy to adjust, which is not liable to stick or jam, which overcomes the pressure of gas, water or oil from the well, which renders it easy to start 40 the drilling of a hole, and which provides uniform pressure upon the bit at any inclination of drilling. Furthermore, the device is convenient to use and economical to manufacture.

According to the present invention, I utilize fluid pressure for securing the feeding pressure in whole or in part. The fluid pressure may be supplied from any convenient source but I preferably employ the 45 water which is pumped down the drill pipe for lubricating the bit and carrying away the drillings. However, air or steam may be used, if desired.

In carrying out the invention, a suitable 50 driving means is provided for rotating the

bit, this means including an appropriate device for permitting longitudinal movement of the drilling bit with respect to the driving means, one of the purposes of which is to allow the bit, which is operatively associated with the driven member, to advance or feed automatically as the hole is cut. This device ordinarily includes a driving member and a driven member so associated together that the rotational movement of the driving means which is connected to the driven member is imparted to the driving member, but allowing the driven member to slide longitudinally with respect to the driving member. With such a device, means 60 operable by fluid pressure is associated in such a manner as to exert a feeding pressure upon the driven member by which the pressure is imparted to the drilling bit.

The feeding pressure device just mentioned, which is operable by a fluid pressure, preferably comprises a cylinder having a piston movable therein under the action of the fluid pressure. Elastic means, such as a spring, is so associated with the cylinder 65 and piston as to oppose the movement of the piston under the operating fluid pressure and transmit this pressure to the cylinder. With these parts arranged in operative position, the fluid pressure, such for example as the drilling liquid, exerts a force upon the piston, compresses the spring or other elastic means and thereby exerts a yielding longitudinal pressure upon the cylinder, which pressure is transmitted to the 70 drilling bit through the above mentioned driven member. The fluid pressure applied to the piston may be controlled from the surface of the ground so as to vary the feeding pressure applied to the bit, but preferably means are provided within the feeding pressure device for limiting the magnitude 75 of the pressure coming from the fluid which can be transmitted to the bit.

This means preferably comprises a channel suitably arranged to bypass the fluid from the top of the piston when the piston has moved forward and compressed the elastic means a predetermined amount. Thus, as soon as the piston opens the bypass 80 the pressure of the fluid is relieved and the feeding pressure exerted on the drilling bit is thereby positively limited. The fluid which is bypassed from the cylinder is preferably arranged to travel around the pis- 85

ton and forward or downward to serve as drilling fluid for the bit.

The feeding pressure device of the invention may be utilized both with apparatus for drilling deep wells and with apparatus for drilling comparatively shallow holes, such as in mining work. For the former purpose, the feeding pressure device is constructed in the form of a completely self-contained unit which is particularly adapted to be lowered down the drill pipe of a rotary drilling rig by means of a cable. When thus lowered into the drill pipe, the device is brought into operative position in coaction with the upper end of the driven member.

Such a feeding pressure device is semi-automatic in its operation for the reason that, although it does not vary the feeding pressure when the drilling bit encounters formations of different hardness, nevertheless it does automatically effectively limit the feeding pressure which can be applied to the bit.

In my prior applications for Letters Patent of the United States, Serial No. 637,761, filed May 9, 1923; Serial No. 681,032, filed December 17, 1923, and Serial No. 712,197, filed May 10, 1924, I have shown and described several methods and apparatus for operating rotary earth-boring bits, particularly abrasive bits both with reciprocating and with rotary drilling rigs. In these prior applications means are provided for operating the drilling bits under such conditions of feeding pressure control as to make the abrasive bit extremely advantageous to use.

All of these prior devices include a driving means and driving and driven members, which members are longitudinally movable with respect to one another. The feeding pressure is supplied by gravity or by means of a spring, and although these prior devices have been found to be operative and successful, my more recent investigations have resulted in the present improvements in the application of the feeding pressure.

In using the drilling apparatus disclosed in these prior applications, the maximum feeding pressure which is applied to the drilling bit is determined by the weight of the bit itself and a portion of the apparatus which is connected thereto, namely, the driven member. In order to increase or decrease the amount of this maximum feeding pressure, it is necessary to increase or decrease the weight of these parts. This may be done, for example, by adding a weight to the top of the driven member or by inserting a hollow sinker between the driven member and the bit.

When a weight is added at the top of the driven member, the friction with the walls of the drill pipe is increased and there is a

possibility of the driven member sticking and preventing the feed of the bit. By securing the additional weight by means of one or more sections of sinker inserted between the driven member and the bit, this liability of sticking is overcome, but, on the other hand, the apparatus is rendered less convenient to operate. If, during the drilling of a hole, a formation of particularly hard rock is encountered, it is necessary to increase the feeding pressure and the entire drilling apparatus must be withdrawn from the hole in order to insert the section or sections of additional weight. This requires a considerable amount of time, particularly when a rotary drilling rig is employed, inasmuch as the drill pipe must be removed from the hole section by section. Again, when starting the drilling of a hole, it may be difficult, on account of the limitation in the height of the derrick, to add sufficient weight to secure the proper feeding pressure.

When operating with the feeding pressure device of the present invention, however, and the drilling bit strikes a particularly hard formation, it is only necessary to hoist the feeding pressure device up to the surface of the ground by means of a cable and then adjust it to secure a greater feeding pressure. This can readily be done, for example, by changing to a heavier spring or by placing washers under the lower end of the spring.

The invention will be better understood by referring to the accompanying drawings which illustrate by way of example two embodiments of the invention. In these drawings:

Fig. 1 is a longitudinal section of the lower end of a drill pipe provided with a slideable joint having driving and driven members and associated with which is the feeding pressure device of the invention. In this view the piston has been moved forward to compress the spring and open the bypass.

Fig. 2 is a longitudinal section of the feeding pressure device removed from the well and showing the piston in released position.

Fig. 3 is a transverse section on line 3—3 of Fig. 1.

Fig. 4 is a transverse section on line 4—4 of Fig. 1.

Fig. 5 is a transverse section on line 5—5 of Fig. 2.

Fig. 6 is a longitudinal section of a modification of the invention as applied to a drilling machine for use in drilling horizontal holes. This view is more or less diagrammatic in character.

Fig. 7 is a transverse section taken on line 7—7 of Fig. 6.

Referring now to the accompanying

drawings, and particularly Figures 1 to 5 inclusive, the drill stem or drive pipe 10 is secured at its lower end by means of a collar 11, to a slideable joint or coupling comprising a driving member 12 and a driven member 13. The driven member 13 is generally circular in cross-section and slides or telescopes through a circular aperture 14 in the driving member. Positive rotational movement is imparted, however, from driving member 12 to driven member 13 by means of oppositely disposed keys or splines 15 which coact with corresponding slots 16 in the driving member.

15 The lower end of driven member 13 is appropriately threaded to receive a drilling bit 17. Any form of bit may be employed but I prefer to use a bit made of abrasive material and comprising, for example, a body 18 of carborundum which is secured in the bit mounting 19 in any suitable manner, such for example as by means of a lead binder 20.

25 The upper end of driven member 13 has an enlarged head 21 which coacts with the top of driven member 12 when the slideable coupling is in extended position to prevent the two members from separating. A longitudinal bore 22 extends throughout the 30 length of driven member 13 for the purpose of conveying drilling fluid to the abrasive bit and for providing a space for the reception of a core when, as in the example shown, a core cutting bit is employed.

35 The feeding pressure device of the invention comprises a cylinder 23 adapted to be lowered by means of a bail 24 and a cable 25 into the drill pipe 10 and rest upon the head 21 of driven member 13. In order to 40 facilitate the engagement of the feeding pressure device with the member 13 when the feeding pressure device is lowered into operating position, the cylinder 23 is provided with an extension 26 of reduced diameter which is adapted to fit within the bore 22 of member 13. Extension 26 is of sufficient length to securely hold the feeding pressure device in operative position. Bore 22 has a flared entrance 27 in head 45 21 to facilitate the entrance of extension 26 therein and to provide a relatively tight seat with a conical surface 28 upon the cylinder 23 for a purpose which will hereinafter appear.

50 Within cylinder 23 there is mounted a slideable piston 29 which is secured to a piston rod 30 by means of nuts 31. On the opposite end of the rod 30 there is secured a guide 32 which slides in a passage-way 33 provided in extension 26. By this construction piston 29 is caused to be freely slideable within cylinder 23. A contraction 33' in the passageway 33 provides a shoulder which acts as a stop for the guide 32, thereby holding piston 29, guide 32 and

their connecting rod 30 in position within the cylinder 23.

A spring 34 is mounted upon piston rod 30 and coacts with the bottom of piston 29 and with a shoulder 35 on the upper surface of contraction 33' so that when piston 29 moves downwardly spring 34 is compressed against shoulder 35. Appropriately positioned in the walls of cylinder 23 is a bypass channel 36, the upper end of which is adapted to be opened by the movement of piston 29 after spring 34 has been compressed a predetermined amount. In Figure 2 the piston is shown above the end of bypass 36, the spring 34 being in extended 80 position, whereas in Figure 1 the piston has moved down and opened the bypass.

When this apparatus is placed in operation, the drill pipe 10 is lowered down the hole until bit 17 strikes the bottom of the 85 hole and the slideable coupling is moved to retract the head 21 above the top of driving member 12. The feeding pressure apparatus is then lowered down the drill pipe by means of cable 25 into the position 90 shown in Figure 1. The drill pipe 10 is now rotated which causes, through the slideable joint, the rotation of bit 17.

Drilling liquid under appropriate pressure is now supplied through drill pipe 10 and 95 because of the close fit which is made by the cone surface 28 with the flaring opening 27 the liquid is confined within the interior of cylinder 21 and forces piston 29 downward against the action of spring 34. This downward movement continues until the piston reaches the position shown in Fig. 1 in which bypass 36 is opened. The drilling liquid can then pass downwardly through bypass 36 and into the passage-way 33, thence through 100 the plurality of channels 37 which are provided in guide 32 for this purpose. Emerging from these channels, the liquid passes through bore 22 downwardly to the cutting surface of the drilling bit. 110

Before the application of the drilling liquid, the feeding pressure upon the bit is provided only by the weight of driven member 15 and the cylinder 23. This may or may not be sufficient to cause the effective operation of the bit, depending upon the design of these parts. When, however, piston 29 is moved downwardly under the action of the drilling fluid the compression of spring 34 transmits this pressure to the cylinder 23 by 120 which it is transmitted to the bit 17. Thus by choosing a spring 34 of appropriate dimensions any desired feeding pressure upon the bit may be obtained.

Referring now to Figures 6 and 7 of the accompanying drawings, the drilling machine here shown comprises a frame 38 which may be mounted upon any appropriate support 39 and within this frame are carried members which correspond to the parts described 130

above. The driving member comprises a longitudinally extending quill 40 which rotates preferably in ball thrust bearings appropriately mounted in frame 38. Quill 40 is 5 mounted at the rear end with a gear 42 meshing with a pinion 43 mounted on the shaft of a driving motor 44. Quill 40 has a longitudinal opening extending from end to end and in the forward end of this opening there 10 is mounted a driven member 45 which is slideable longitudinally and which is provided with keys 46 similar to keys 15 of Figure 1. Driven member 45 is thus positively rotated by quill 40 and at the same time is slideable 15 longitudinally therein. Upon its forward end driven member 45 carries a bit 47, preferably of abrasive material. An intermediate section of drill stem 48 may be interposed between driven member 45 and the bit, if de- 20 sired, as is shown in Figure 6.

Driven member 45 extends through to the rear of the drilling machine and has a cylindrical bore 49 extending from end to end thereof. A piston 50 is mounted within this 25 bore upon a piston rod 51 as before. This rod is, however, slideable within a guide 52 which is permanently fixed in position within bore 49 but provided with a plurality of water channels 53. Guide 52 acts as a stop 30 against which a spiral spring 54 presses under the movement of piston 50, this spring being mounted upon the piston rod 51.

The interior of quill 40 is chambered out 35 at 55 to a diameter somewhat larger than the driven member 45 to allow for the passage of drilling fluid around the piston and to afford means for limiting the longitudinal movement of driven member 45. For this latter purpose a sleeve 56 is rigidly mounted on the 40 exterior of driven member 45. The forward and rear ends of this sleeve form shoulders adapted to coact with the end walls of chamber 55 to stop the movement of member 45 in both directions.

45 Drilling fluid is applied at the right hand end of the machine and passes through bore 49 to the piston. The pressure of this fluid moves the piston forward to compress the spring and in Figure 6 the piston is shown in 50 the forward position where it has opened a pair of ports 57 allowing the fluid to escape into chamber 55. From this chamber the fluid passes through a second pair of ports 58 back into the bore 49 below the piston 50. 55 The liquid then passes onwardly through channels 53 and thence forward to lubricate the bit.

In this apparatus the feeding pressure is 60 controlled by means of spring 54 and regardless of the pressure of the drilling fluid used, it is impossible for the machine operator to apply more than the predetermined feeding pressure to the drilling bit, the feeding pressure thus being automatically limited. When 65 drilling a horizontal hole with this appara-

tus, the weight of the moving parts does not affect the feeding pressure applied to the bit and this pressure is exerted entirely by the compression of spring 54 under the influence of the fluid pressure applied to piston 50. In 70 other words, the feeding pressure is applied entirely by the fluid pressure regulating device. During the drilling of holes which are inclined either upwardly or downwardly with respect to the horizontal, the weight of 75 the moving parts, of course, tends to add to or subtract from the feeding pressure applied by the fluid pressure regulator, but the weight of these moving parts is comparatively small and, even when drilling vertical 80 holes, has a negligible effect upon the feeding pressure exerted by the fluid pressure device. Hence, the feeding pressure is substantially uniform at all inclinations of drilling.

In drilling deep wells with the drilling apparatus illustrated in Figures 1 to 5 inclusive, the ease with which the feeding pressure regulator of the invention can be adjusted to meet various conditions of drilling is an important advantage. For example, if the drilling bit passes through a relatively soft formation to a relatively hard rock, it will probably be desirable to increase the feeding pressure applied to the bit in order to cut through the harder material at a maximum rate of speed. In order to make the adjustment for this increased feeding pressure, it is only necessary to hoist the removable feeding pressure regulator shown in Figure 2 to the surface of the ground by means of the cable 25 and then either insert a larger spring 34 or place washers upon shoulder 35 in order to cause a greater compression in spring 34 before piston 29 opens the bypass 36. This operation of hoisting and adjusting is not only practicable but is convenient from the driller's point of view.

An additional advantage of the present feeding pressure regulator is the reduction 110 or elimination of any tendency that may exist in the slideable coupling to stick or jam. This tendency is overcome because of the application of a positive and controllable fluid pressure for producing the pressure 115 upon the bit.

In the drilling of wells for oil, water or 120 gas, it not infrequently happens that these elements are encountered in the earth under such pressure as to seriously interfere with the drilling operations. However, when employing the feeding pressure apparatus of the invention, this pressure is overcome by the pressure of the drilling fluid, and inasmuch as the feeding pressure exerted upon the drilling bit depends upon the difference in pressure between the opposite sides of the piston, the feeding pressure will not be lessened by the pressure of oil, water or gas 125 which tend to flow up the hole being drilled.

The feeding pressure regulator of the invention provides a convenient and efficient means for obtaining the required feeding pressure in the starting of a hole because the 5 regulator has a relatively small diameter, is light in weight and can be readily manipulated by a derrick. The employment of long sections of a sinker or other weight in order to secure the appropriate feeding pressure 10 is thence avoided.

A further advantage which is not to be overlooked resides in the economy of manufacturing. The slideable joint, the members of which are connected by straight longitudinal keys, is capable of being made easily and cheaply, the principal process consisting of drawing the material through suitable dies which can be done at the steel mill. The machining of the slideable joint is 15 thereby limited to the cutting of the threads at both ends. The parts of the fluid pressure regulator are few in number and of simple form. They can all be made by simple casting, forging and machining operations.

I claim:

1. In an earth-boring apparatus the combination of an earth-boring bit, a driving element extending down the hole being 30 drilled for rotating the bit, a device for connecting the bit to the lower end of the driving element for imparting positive rotation to the bit and for permitting longitudinal movement thereof with respect to the driving element, and means operable by fluid pressure and associated with said device for exerting a feeding pressure upon the bit.

2. In an earth-boring apparatus the combination of an earth-boring bit, a driving 40 element extending down the hole being drilled for rotating the bit, a device for connecting the bit to the lower end of the driving element for imparting positive rotation to the bit and for permitting longitudinal movement thereof with respect to the driving element, said device including driving and driven members, and means operable by fluid pressure and associated with the driven member for exerting a feeding pressure 50 upon the bit.

3. A feeding pressure device for earth-boring bits comprising, a cylinder adapted to receive fluid pressure, a bit operatively connected thereto, a piston movable therein, and elastic means for opposing said movement and for transmitting to the cylinder pressure applied to the piston.

4. A feeding pressure device for earth-boring bits comprising, a cylinder, a bit operatively connected thereto, a piston movable therein under the influence of fluid pressure, and elastic means associated with the piston and cylinder for transmitting by the compression of said elastic means a longitudinally acting force to the cylinder.

5. A feeding pressure device for earth-boring bits comprising, a cylinder, a bit operatively connected thereto a piston movable therein under the action of fluid pressure, and a spring coacting with the cylinder and piston to oppose said movement and for transmitting to the cylinder by the compression of the spring pressure applied to the piston.

6. A feeding pressure device for earth-boring bits comprising, a cylinder, a bit operatively connected thereto a piston movable therein under the action of fluid pressure, elastic means for opposing said movement and for transmitting to the cylinder pressure applied to the piston, and means for stopping the movement of the piston when the pressure applied thereby to the cylinder reaches a predetermined amount.

7. A feeding pressure device for earth-boring bits comprising, a cylinder, a bit operatively connected thereto, a piston movable therein under the action of fluid pressure, elastic means for transmitting by the compression thereof a longitudinally acting force to the cylinder, and means for stopping the movement of the piston when the compression in the elastic means reaches a predetermined amount.

8. A feeding pressure device for earth-boring bits comprising, a cylinder, a bit operatively connected thereto, means for supplying fluid pressure thereto, a piston movable in the cylinder under the action of said pressure, elastic means for transmitting by the compression thereof a longitudinally acting force to the cylinder, and means for relieving said fluid pressure when the longitudinally acting force reaches a predetermined amount.

9. A feeding pressure device for earth-boring bits comprising, a cylinder, a bit operatively connected thereto, means for supplying fluid pressure thereto, a piston movable in the cylinder under the action of said pressure, elastic means for transmitting by the compression thereof a longitudinally acting force to the cylinder, and means under the control of the piston for relieving said fluid pressure when the longitudinally acting force reaches a predetermined amount.

10. A feeding pressure device for earth-boring bits comprising, a cylinder, a bit operatively connected thereto, means for supplying fluid pressure thereto, a piston movable in the cylinder under the action of said pressure, elastic means for transmitting by the compression thereof a longitudinally acting force to the cylinder, the cylinder having a by-pass associated therewith for relieving said fluid pressure and adapted to be uncovered by the movement of the piston when the longitudinally acting force reaches a predetermined amount.

11. A feeding pressure device for earth-boring bits comprising, a cylinder, a bit operatively connected thereto, means for supplying fluid pressure thereto, a piston movable in the cylinder under the action of said pressure, a spring coacting with the cylinder and piston to oppose said movement and for transmitting to the cylinder by the compression of the spring pressure applied to the piston, and means for relieving said fluid pressure when the force applied to the cylinder by the piston reaches a predetermined amount. 70
12. A feeding pressure device for earth-boring bits comprising, a cylinder, a bit operatively connected thereto, means for supplying fluid pressure thereto, a piston movable in the cylinder under the action of said pressure, a spring coacting with the cylinder and piston to oppose said movement and for transmitting to the cylinder by the compression of the spring pressure applied to the piston, and means under the control of the piston for relieving said fluid pressure when the force applied to the cylinder by the piston reaches a predetermined amount. 75
13. In an earth-boring apparatus the combination of an earth-boring bit, driving means therefor, means for supplying drilling liquid to the bit under appropriate pressure, and a feeding pressure device associated with the bit comprising, a cylinder, a piston movable therein under the pressure of the drilling liquid, elastic means for transmitting by the compression thereof a longitudinally acting force to the cylinder, and means for relieving the pressure of the drilling liquid when the longitudinally acting force reaches a predetermined amount. 80
14. In an earth-boring apparatus the combination of an earth-boring bit, driving means therefor, means for supplying drilling liquid to the bit under appropriate pressure, and a feeding pressure device associated with the bit comprising, a cylinder, a piston movable therein under the pressure of the drilling liquid, elastic means for transmitting by the compression thereof a longitudinally acting force to the cylinder, and means under the control of the piston for relieving the pressure of the drilling liquid when the longitudinally acting force reaches a predetermined amount. 85
15. In an earth-boring apparatus the combination of an earth-boring bit, driving means therefor, means for supplying drilling liquid to the bit under appropriate pressure, and a feeding pressure device associated with the bit comprising, a cylinder, a piston movable therein under the pressure of the drilling liquid, a spring coacting with the cylinder and piston to oppose said movement and for transmitting to the cylinder by the compression of the spring pressure applied to the piston, and means for relieving said fluid pressure when the force applied to the cylinder by the piston reaches a predetermined amount. 90
16. In an earth-boring apparatus the combination of an earth-boring bit, driving means therefor, and a feeding pressure device associated therewith comprising, a cylinder adapted to receive fluid pressure, a piston movable therein under the action of said pressure, and elastic means for opposing said movement and for transmitting to the cylinder pressure applied to the piston. 95
17. In an earth-boring apparatus the combination of an earth-boring bit, driving means therefor, and a feeding pressure device associated therewith comprising, a cylinder adapted to receive fluid pressure, a piston movable therein under the action of said pressure, elastic means for transmitting by the compression thereof a longitudinally acting force to the cylinder, and means for relieving said fluid pressure when the longitudinal acting force reaches a predetermined amount. 100
18. In an earth-boring apparatus the combination of an earth-boring bit, driving means therefor, and a feeding pressure device associated therewith comprising, a cylinder adapted to receive fluid pressure, a piston movable therein under the action of said pressure, elastic means for transmitting by the compression thereof a longitudinally acting force to the cylinder, and means under the control of the piston for relieving said fluid pressure when the longitudinally acting force reaches a predetermined amount. 105
19. In an earth-boring apparatus the combination of an earth-boring bit, driving means therefor, and a feeding pressure device associated therewith comprising, a cylinder adapted to receive fluid pressure, a piston movable therein under the action of said pressure, a spring coacting with the cylinder and piston to oppose said movement and for transmitting to the cylinder by the compression of the spring pressure applied to the piston, and means for relieving said fluid pressure when the force applied to the cylinder by the piston reaches a predetermined amount. 110
20. In an earth-boring apparatus the combination of an earth-boring bit, driving means for rotating the bit including driving and driven members movable longitudinally relative to one another, and a feeding pressure device associated with the driven member comprising, a cylinder adapted to receive fluid pressure, a piston movable therein under the action of said pressure, and elastic means for opposing said movement and for transmitting to the cylinder pressure applied to the piston. 115
21. In an earth-boring apparatus the com- 120
- 125
- 130

5 bination of an earth-boring bit, driving
means for rotating the bit including driving
and driven members movable longitudinally
relative to one another, and a feeding pres-
sure device associated with the driven mem-
ber comprising, a cylinder adapted to re-
ceive fluid pressure, a piston movable therein
under the action of said pressure, elastic
means for transmitting by the compression
thereof a longitudinally acting force to the
cylinder, and means for relieving said fluid
pressure when the longitudinally acting
force reaches a predetermined amount.

10 22. In an earth-boring apparatus the com-
bination of an earth-boring bit, driving
means for rotating the bit including driving
and driven members movable longitudinally
relative to one another, and a feeding pres-
sure device associated with the driven
member comprising, a cylinder adapted to
receive fluid pressure, a piston movable therein
under the action of said pressure, elastic
means for transmitting by the compression
thereof a longitudinally acting force to the
cylinder, and means under the control of the piston for relieving said fluid
pressure when the longitudinally acting
force reaches a predetermined amount.

15 23. In an earth-boring apparatus the com-
bination of an earth-boring bit, driving
means for rotating the bit including driving
and driven members movable longitudinally
relative to one another, and a feeding pres-
sure device associated with the driven mem-
ber comprising, a cylinder adapted to receive
fluid pressure, a piston movable therein
under the action of said pressure, a spring
coacting with the cylinder and piston to op-
pose said movement and for transmitting to
the cylinder by the compression of the
spring pressure applied to the piston, and
means for relieving said fluid pressure when
the force applied to the cylinder by the pis-
ton reaches a predetermined amount.

20 24. In an earth-boring apparatus, the com-
bination of a drill pipe provided with a slid-
able connection having driving and driven
members, a drilling bit operatively connect-
ed to the driven member and a feeding pres-
sure device operable by fluid pressure and

capable of being lowered through the drill
pipe into operative position with respect to
the driven member.

25. In an earth-boring apparatus, the com-
bination of an earth-boring bit, a drill stem 55
therefor, a slidable connection therebetween
having a driven member operatively connect-
ed to the bit and provided with a seat at its
upper end, and a removable feeding pressure
device adapted to engage said seat and there-
by coat with the driven member.

30 26. In an earth-boring apparatus, the com-
bination of an earth-boring bit, a drill stem
therefor, a slidable connection therebetween
having a driven member operatively connect-
ed to the bit, said member having a passage-
way therethrough, and a feeding pressure
device operable by fluid pressure and asso-
ciated with said driven member, said device
being provided with a bypass connecting 70
with the passage-way in the driven member
so as to supply drilling fluid to the bit.

35 27. In an earth-boring apparatus, the com-
bination of a drill pipe provided with a slid-
able connection having driving and driven
members, a drilling bit operatively connected
to the driven member, and a feeding pressure
device capable of being lowered through the
drill pipe into operative position with re-
spect to the driven member.

40 28. In an earth-boring apparatus, the com-
bination of a drill pipe provided with a slid-
able connection having driving and driven
members, a drilling bit operatively connect-
ed to the driven member and a feeding pres-
sure device capable of being lowered through
the drill pipe comprising a cylinder adapted
to rest upon the driven member when in op-
erative position, a piston movable in the cyl-
inder under the pressure of the drilling liq-
uid, elastic means for transmitting said liq-
uid pressure by the compression of said
elastic means to the cylinder and thereby to
the drilling bit, and means for relieving the
pressure of the drilling liquid when the pres-
sure upon the bit reaches a predetermined
amount.

45 29. In testimony whereof I affix my signature.

EGGLESTON SMITH.
